(57) **CLAIM**

The ornamental design for a computer, as shown and described.

DESCRIPTION

FIG. 1 is a front elevational view of a computer showing our new design;

FIG. 2 is a rear elevational view thereof;

FIG. 3 is a top plan view thereof;

FIG. 4 is a bottom plan view thereof;

FIG. 5 is a right-side elevational view thereof;

FIG. 6 is a left-side elevational view thereof; and,

FIG. 7 is a front, top and left-side perspective view thereof.

The even-dash broken lines in the drawings illustrate portions of the computer that form no part of the claimed design. The long-dash short-dash broken lines define the boundaries of the claim, which extends to the boundaries but does not include the boundaries.
